(57) **CLAIM**

The ornamental design for a laryngoscope handle, as shown and described.

DESCRIPTION

FIG. 1 is a front elevation view of my design for a laryngoscope handle;

FIG. 2 is a right side view thereof;

FIG. 3 is a back view thereof;

FIG. 4 is a left side view thereof;

FIG. 5 is a bottom view thereof;

FIG. 6 is a top view thereof; and,

FIG. 7 is a perspective view thereof.

The broken line showing is for illustrative purposes only and forms no part of the claimed design.
